PAPER CARRIAGE FOR ACCOUNTING MACHINES

Walter A. Anderson, Bridgeport, Conn., assignor to Underwood Elliott Fisher Company, New York, N. Y., a corporation of Delaware

Application February 26, 1938, Serial No. 192,675

2 Claims. (Cl. 197—128)

This invention relates to paper carriages for accounting machines, and is illustrated in connection with the type of carriage to be used on the machine disclosed in the application of Oscar J. Sundstrand, Serial No. 581,800, filed December 18, 1931. It is adapted to be used in association with the improvement disclosed in the application of Walter A. Anderson, Serial No. 150,367, filed June 25, 1937, and is an improvement over the mechanism disclosed in United States Patent No. 2,060,954, issued to Oscar J. Sundstrand on November 17, 1936.

The primary object of the present invention is to provide a mechanism that will facilitate the insertion and feeding of both front fed and rear fed paper.

With this and incidental objects in view, the invention consists in certain novel features of construction and combinations of parts, the essential elements of which are set forth in appended claims, and a preferred embodiment of which is hereinafter described with reference to the drawings which accompany and form part of the specification.

In said drawings:

Figure 1 is a perspective view of the improved carriage.

Figure 2 is a right side elevation of the carriage, Figure 3 is a right side elevation of the portion of the carriage showing the front feed mechanism in closed position,

Figure 4 is a right side elevation of a portion of the carriage showing the auxiliary paper chute in position on the carriage and showing the front feed lip opened to accommodate paper fed through the auxiliary chute,

Figure 5 is a perspective view of the roller trucks for the rear fed paper and shows the mounting and adjusting means for these trucks,

Figure 6 is a perspective view showing the adjustable edge guides for the front fed paper,

Figure 7 is a perspective view of the tally roll holder,

Figure 8 is a rear elevation of one of the latches for the upper front feed paper guides,

Figure 9 is a front elevation, partly in section, showing the latch for holding the tally roll holder in position,

Figure 10 is a right side elevation of one of the lower guides for the front fed paper,

Figure 11 is a right side elevation of the platen advancing mechanism,

Figure 12 is a perspective view showing the auxiliary paper chute in position on the carriage

and also illustrating the tear plate for the rear fed paper,

Figure 13 is a left side elevation of several of the parts shown in Figure 12, and

Figure 14 is a plan view of parts of the journal sheet holder shown in Figure 2.

CARRIAGE IN GENERAL

Referring to Figure 1, the carriage is mounted for movement along a track 1. The track is provided with grooves 2 (Figure 2) to receive rolls 3, received also by oppositely disposed grooves in carriage frame 4. As the carriage moves from right to left, it is stopped in various columnar positions so that type bars 5 on the accounting machine may print against platen 6 (Figure 1). The mechanism for tabulating the carriage from column to column and for returning it to its initial position is disclosed in application Serial No. 581,800.

The carriage is adapted to accommodate rear fed paper such as the continuous journal sheet 7 and a tally roll 8, as well as front fed paper such as a ledger sheet 11.

Mechanism for rotating the platen

Referring to Figures 1 and 11, the platen 6 may be rotated manually by knobs 12 secured to each end of the platen shaft 13, and may be rotated automatically during operations of the machine by a feed pawl 14 (Figure 11). The feed pawl is pivoted at 15 to a lever 16 pivoted on the carriage frame at 17. A spring 18 is secured to feed pawl 14 and tends to rotate the feed pawl clockwise about its pivot 15. A feed adjusting bracket 21 is pivoted on the carriage at 22 and has an arm 23 connected to the main body portion of the bracket by a yoke 24. Arm 23 carries a stud 25 lying between the arm and the main portion of the bracket. This stud acts as a stop to limit the clockwise movement of feed pawl 14 about its pivot. A detent 26 is pivoted on the carriage at 27 and has notches 28 in its right hand edge cooperating with a stud 31 on bracket 21 to hold the bracket in any adjusted position. A spring 32 connected to detent 26 holds notches 28 in engagement with stud 31.

As explained in Patent No. 2,060,954, the platen is rotated during certain operations of the machine by lever 16 being rotated counter-clockwise about its pivot 17. This moves lever 16 to the left, its upper edge remaining in contact with stud 25 through the tension of spring 18. When bracket 21 is in the position shown in Figure 11, and feed pawl 14 is moved to the left during an

- operation of the machine, the left end of the feed pawl passes under tooth 33 on ratchet wheel 34 secured to platen shaft 13, but contacts tooth 35 so that further movement of the feed pawl to its dotted line position shown in Figure 11 rotates the platen one line space. A spring pressed 5
detent, including two similar levers 36, is pivoted at 37, and carries a roller 38 situated between the two levers at their left ends (see also 10
Figure 1). A spring 41 holds roller 38 in engagement with the teeth on ratchet wheel 34 to hold the platen in advanced position.

- If the operator desires to have the platen advance two line spaces during one operation, or, 15
on the other hand, not advance at all, it is only necessary for him to grasp the left end 42 of bracket 21 and move it up or down. A suitable index reading "0" "1" "2" is provided on the carriage side plate 43 to indicate the position of 20
bracket 21. When the bracket is in its upper position, the left end of feed pawl 14 is elevated sufficiently to engage tooth 33 instead of tooth 35 and thereby rotate the platen two line spaces instead of one in its movement to the left. 25
When bracket 21 is in its lower position, the left end of feed pawl 14 is lowered to such an extent that it will engage neither of the teeth 33, 35 when it is moved to the left, thereby failing to advance the platen.
- 30 *Mechanism for guiding and feeding rear fed paper*

Referring to Figures 1 and 2, the rear fed paper is shown in the form of a continuous journal sheet 7 and a talley roll 8. The journal sheet 7 is supported on a spindle 44 rotatably mounted between side plates 45 and 46, in turn supported on a square rod 47 held securely between the carriage side plates by two screws, one of which 35
is shown at 48 (Figure 1). The plates are supported at their left ends by a rod 49 secured in the carriage side plates by two screws, one of which is shown at 50 (Figure 1). Plates 45 and 46 each have secured thereto a sleeve 50a (Figure 14) carrying a bracket 51 into which is threaded a set screw 52. By this means, plates 45 and 46 may be moved along rod 47 to the required position and secured in place by tightening set screw 52. Each of the plates 45 and 46 40
45 carries an arm 53 having a portion 54 bent at a right angle and pivoted on short rods 55 (one being shown in Figure 14) secured in the side plates. A spring 56 is secured to each arm 53 and to the corresponding plate to hold the arm 50
55 against the journal sheet 7. These arms 53 serve to keep the journal sheet taut.

As the journal sheet passes from the roll it first passes over a paper table 57 extending across the entire width of the carriage and having at its opposite ends flanges 58. The flanges are apertured to receive the opposite ends of a rod 61 secured to the side plates of the carriage by two screws, one of which is shown at 62 (Figure 1). The paper table 57 extends downwardly to a point quite close 60
65 to the platen and is held at its lower end securely in the carriage frame by screws (not shown). A pair of paper guides 63 and 64 lie over paper table 57 and are curved at their upper ends, as shown in Figure 2. Brackets such as 65 are secured to guides 63 and 64 and are apertured to receive rod 61. Brackets 65 grip rod 61 sufficiently to retain the paper guides in any position 70
75 to which they are adjusted.

After passing over the paper table 57 the journal sheet then passes between the platen and rear

feed rolls 66 (see also Figure 5). Feed rolls 66 are each supported between flanges 67 of a plate 68. A pair of short arms 71 project upwardly from plate 68 and are bent slightly forwardly of the platen. A short flange 72 also extends upwardly from plate 68 and is bent forwardly at the plate (see also Figure 2). A pair of ears 73 extend upwardly from plate 68 and are apertured to receive a rod 74 secured in the side plates of the carriage. A U-shaped bracket 75 is apertured to receive rod 74 and is also apertured to receive a flat sided shaft 76 journaled in the carriage side plates. A pair of springs 77 are secured to the bracket 75 and to flange 72 on plate 68 to tension plate 68 and roll 66 clockwise about rod 74. Manipulative levers 78 are secured to each end of shaft 76.

Referring to Figure 2, it will be noted that when the feed rolls 66 lie in their operative position against the platen, one of the longer flat sides of shaft 76 lies against short arms 71. When it is desired to move the feed rolls away from the platen, it is only necessary to rotate one of the levers 78 a slight extent. This causes one of the edges of shaft 76 to move arms 71 to the left (Figure 2), and rotate the plate 68 and roll 66 counter-clockwise about rod 74.

After passing between the platen and the feed rolls 66 the paper then continues around the platen and passes under a pressure finger 81. This finger is secured to substantially the mid portion of a tear plate 82 (see also Figures 12 and 13) secured to a square rod 83 and having a serrated rear edge 84. Rod 83 is pivoted at its opposite ends in the carriage side plates 43. A finger piece 85 (Figure 13) is provided on the left end of rod 83 and carries a stud 86 that bears against the upper edge of side plate 43 to limit the movement of the finger piece. A light spring 87 secured to the finger piece and to the carriage side plate tensions the finger piece and pressure finger 81 clockwise about rod 83, as seen in Figure 13, to normally hold the pressure finger lightly against the platen. When feeding the journal sheet around the platen, the operator moves the finger piece 85 slightly counter-clockwise (Figure 13) to raise pressure finger 81 away from the platen. The paper is then inserted between the pressure finger and the platen, after which the finger piece 85 is released. Since the pressure of finger 81 on the paper is very light, it does not interfere with the feeding movement of the paper. Further rotation of the platen moves the paper rearwardly under tear plate 82. Another plate 88 is suspended under tear plate 82 and is supported by ears 91 and 92 apertured to receive rod 83. The ears fit loosely on rod 83 so that movement of rod 83 does not effect plate 88. Two similar ears 93, one of which is shown in Figure 12, project downwardly from the plate, their lower ends resting on the lower portion of paper table 57. By these ears 91, 92 and 93, plate 88 is supported in the position shown in Figures 12 and 13 to direct the journal sheet upwardly after it leaves the platen, thus preventing its contact too soon with the portion of the journal sheet that is moving downwardly toward the platen, and thereby preventing the leading edge from being again carried around the platen. After the journal sheet passes to the rear of tear plate 82, it passes over the journal sheet roll and then rests on two guide arms 94, one situated at each side of the journal sheet. One of these arms is shown in Figures 1 and 2. Each arm 94 is provided with a U-shaped bracket 95 to hold the journal sheet against 75

movement laterally of the carriage as the carriage tabulates from column to column. Arms 94 are attached to plates 45 and 46 by sleeves 50a (Figure 14) and rods 55.

- 5 A tally roll holder having side plates 96 connected by a rod 97 and a bracket 98 is supported on the carriage to the rear and at one side of the journal sheet 1, as shown in Figure 1. The tally roll holder is placed on the carriage by first being hooked over rod 47 (Figure 2) and then being lowered over a rod 101. The tally roll holder is held in contact with rod 101 by the parts shown in Figure 9. As shown in this figure, a sleeve 102 is secured on rod 101 by a set screw 103 threaded 10 in the sleeve. Another sleeve 104 is slidable on rod 101 and is connected with sleeve 102 by a link 105 having a slot 106 to provide lost motion between the two sleeves. A spring 107 urges sleeve 104 away from sleeve 102 so as to hold shoulders 20 108 on sleeves 102 and 104 in engagement with recesses 111 (Figure 7) on side plates 96. When lowering the side plates over rod 101 it is only necessary for the operator to move sleeve 104 toward sleeve 102, then lower the side plates until 25 rod 101 is within recesses 111, and then release sleeve 104 to the tension of spring 107. This latches the tally roll holder securely in place. An arm 112 (Figure 7) is pivoted in upstanding ears at the opposite ends of bracket 98 and is pulled 30 toward the tally roll by a spring 113. This arm serves to keep the tally roll taut. A short finger 114 extends upwardly from bracket 98 to prevent excessive counter-clockwise movement of arm 112 when the tally roll is removed from the holder. 35 The tally roll is supported in the holder on a rod 115 having a knurled knob 116 at one end and a threaded portion at its other end received in an internally threaded stud 117 secured to the right hand side plate 96 (Figure 7).

40 *Mechanism for guiding and feeding front fed paper.*

For introducing front fed sheets, upper paper guides 118 (Figures 1 and 2) and lower paper guides 121 are provided. The left hand upper guide 118 is provided with an edge guide 122, and the right hand lower guide 121 is provided with an edge guide 123, the latter being flared outwardly to the right at its upper portion. Guides 50 118 are supported on rods 124 that extend through lower guides 121 and are secured to arms 125. Arms 125 are in turn secured by screws 126 and 127 (see also Figure 12) to arms 128 and 131 pivoted on semi-cylindrical studs 132 and are held in 55 engagement therewith by studs 134. The semi-cylindrical studs 132 are secured to spacing plates 133, which in turn are secured to carriage side plates 43. The upper ends of guides 118 (Figures 1 and 2) are supported by a rod 135 secured to 60 two arms 136, in turn supported by rods 49 and 137. Guides 118 are connected to rod 135 by brackets 138 slidably mounted on guides 118. This sliding movement is obtained, as shown in Figure 8, by having brackets 138 each slotted to 65 receive three bolts 141 secured in guide 118. A spring 142 extending from the bracket to the upper bolt 141 tensions the bracket upwardly. A sleeve 143 for each bracket is secured on rod 135 by a set screw 144, between the two side flanges 70 of the brackets, to prevent lateral movement of the latter.

The lower paper guides 121 have downwardly extending flanges 145 and 146 (Figures 1, 2 and 10) to form a paper chute to direct the paper 75 downwardly between the platen and the type

bars (Figure 2). Paper guides 121 are supported on a rod 147 secured to arms 128 and 131 by screws 126. A key pin 148 (Figure 10) is inserted in the semi-circular grooves provided in rod 147 and in the downwardly extending flanges 5 151 (Figures 1 and 10) of guide 121. Key pin 148 prevents guide 121 from rotating on rod 147, but allows it to be adjusted axially of the rod to accommodate journal sheets of different widths. The key pin may be secured in 10 guide 121 by any suitable means.

After the paper passes downwardly through the chute, it is directed under the platen first by the upper portion of a plate 152 secured to the frame of the accounting machine. One or 15 more deflectors 153 are provided adjacent type bars 5 and have surfaces 154 to prevent the paper from catching on the rear ends of the type if the paper should have a tendency to curl in this direction. Plate 152 deflects the 20 paper toward a front feed lip 155 (Figures 2 and 5) secured on a square rod 156 pivoted in the carriage side plates 43.

Further insertion of the paper brings it between edge guides 157 (Figure 6), adjustably 25 mounted on rods 158 secured in the carriage side plates 43. Thumb screws 161 (Figures 2 and 6) retain the guides 157 in any adjusted position.

The paper is then deflected upwardly between the rear feed rolls 66 and guide plate 162 suitably secured between the carriage side plates. Further movement brings the paper into contact with the lower edges of deflectors 163 supported on rods 74 and 137. The paper then continues rearwardly between deflectors 163 and 35 plate 162 until it strikes adjustable paper stops 164, one of which is shown in Figure 2. Stops 164 may be adjusted along plate 162 by turning a knob 165 (Figure 1). This adjustment permits the front fed paper to be inserted in the 40 machine to different extents. The details of the adjustable stop mechanism are disclosed in application Serial No. 92,164.

After the paper is fully inserted, it is necessary to bring it in contact with the platen at 45 the printing point, and also to hold it firmly against the platen at some point for the purpose of line spacing. It is also necessary to move the paper guides 121 and the adjacent structure to the rear to allow type bars 5 to rise the necessary 50 extents during the machine operations in the several columnar positions.

To bring the paper against the platen at the printing point, front feed lip 155 (Figure 2) is mounted for pivotal movement whereby it can 55 be moved to a position quite close to the platen, as shown in Figure 3. This serves to bend the paper around the platen from a position below the printing point. Pressure rolls 166 (Figures 1, 2 and 3) are provided to bend the paper around the platen from a position above the printing point, and also to hold the paper firmly against the platen for line spacing. The operative position of these rolls is shown in Figure 3. Rolls 166 are pivotally mounted in supporting brackets 60 167 supported on a square rod 168 secured to arms 128 and 131 by screws 127 (Figures 1 and 12). The pressure rolls and their supporting brackets may be adjusted along rod 168, and are held in any adjusted position by thumb screws 65 171.

The movement necessary to bring rolls 166 into effective position is sufficient to move guides 121 and their adjacent mechanism to the rear a sufficient distance to be out of the path of type 75

bars 5. The rearward movement of these parts is also used to pivot front feed lip 155. In moving the parts from the position shown in Figure 2, which may be called the open position of the front feed mechanism, to the position shown in Figure 3, which may be called the closed position, rolls 166 and lower paper guides 121 move to the rear, along with arms 128 and 131 and rods 124, 147 and 168, the entire assembly pivoting about studs 132. As rods 124 (Figures 2 and 3) move rearwardly about studs 132 as a pivot, upper paper guides 118 must move relatively to brackets 138 a slight extent. The slideable connection shown in Figure 8 between these parts accommodates this relative movement. The closing movement of the above parts moves the front feed lip from its open position shown in Figure 2 to its closed position shown in Figure 3 by the following parts.

20 A pair of arms 172 (Figures 1, 2, 3 and 5) are secured at the opposite ends of a plate 173 pivoted at 174 in the carriage side plates. A spring 175 (Figures 2 and 3) tensions arms 172 and plate 173 clockwise about their pivot 174, the clockwise movement being limited by studs 176 (Figures 1 and 12) in arms 128 and 131. The front feed lip 155 is provided with ears 177 at its opposite ends, the ears lying directly behind arms 172. When the front feed mechanism is open, arms 172 and front feed lip 155 lie in the position shown in Figure 2. When the mechanism is closed, spring 175 draws arms 172 to the rear, and through contact with ears 177, rocks the front feed lip upwardly to the position shown in Figure 3, square rod 156 pivoting to accommodate this movement. When the front feed mechanism is again opened, studs 176 move arms 172 forward, allowing a spring 178 (Figures 2 and 5), secured to a downwardly extending arm 181 of front feed lip 155, to move the front feed lip to its open position shown in Figure 2.

The front feed mechanism is held in either its open or closed position by a detent 182 (Figures 2 and 12) pivoted on arm 128 at 183. Detent 182 is provided with a spring 184 to hold either of two notches in the detent in engagement with a stud 185 secured in the left hand carriage side plate 43.

Auxiliary paper chute for front fed paper

50 At times it is necessary to insert front fed sheets in the machine and have what is known as "headings" printed on them. A heading is merely a number that represents a balance brought forward from a previous sheet. The headings are ordinarily printed at the top of the new sheets and are all printed in the same location on the sheets. Since, during the printing of these headings, it is not necessary to tabulate the carriage from one column to another, nor to line space the paper, it is not necessary that pressure rolls 166 be used to hold the paper against movement in the platen or to assist in feeding the paper. It would, therefore, be desirable to operate the machine to print these headings without the operator having to open and close the front feed mechanism between each operation. However, as mentioned before, it cannot be operated while the front feed mechanism is open, because these parts would interfere with the necessary upward movement of type bars 5. The following parts have, therefore, been provided for directing front fed paper into the machine with the upper parts of the front feed mechanism closed.

Referring to Figures 4 and 12, an auxiliary paper chute 186 is provided with side walls 187 secured at the opposite ends of front and back plates 188 and 191. Plates 188 and 191 are flared at their upper portions, as shown in Figure 4, to facilitate insertion of sheets. The mid portions of plates 188 and 191 are indented at 192 and 193 to provide ample space for the hand of the operator. The auxiliary chute 186 is supported on the front feed mechanism by its side walls 187 being hooked over rod 147 and resting against rod 168. A latch 194 is pivoted to the right and side wall 187 at 195 and has a hook 196 held in contact with rod 168 by a spring 197.

When auxiliary chute 186 is used for inserting front fed sheets, it is necessary to open front feed lip 155 in some manner other than by the customary opening of the front feed mechanism as described above. For this purpose a lever 198 (Figures 4 and 12) is provided. This lever is 20 situated outside the left hand carriage side plate 43 so that it can be manipulated by the operator. A cam 201 is connected to lever 198 by a short shaft 202 (Figure 4). Movement of lever 198 from the position shown in Figure 3 to that shown in Figure 4 moves front feed lip 155 from the position shown in Figure 3 to that shown in Figure 4 through the contact of cam 201 with a short flange 203 (Figures 3, 4 and 12) secured to rod 156 at its left end. A detent 204 is pivoted on the carriage side plate at 205 and is held in contact with a stud 206 on cam 201 by a spring 207. Detent 204 is provided with two notches to retain lever 198 in either of its two positions.

The sheets on which the headings are to be printed may now be inserted downwardly between plates 188 and 191. They are deflected rearwardly by plate 152 and pass between front feed lip 155 and the platen, the front feed lip 40 having been opened by lever 198 prior to the insertion of the sheet. Further insertion of the sheet causes it to move rearwardly, in the same manner as described above for other front fed paper, until it is stopped by paper stops 164.

A finger 208 (Figure 12) is secured to the auxiliary chute and extends downwardly to a position quite close to the platen. This finger 208 holds the paper sufficiently close to the platen at the printing point to make it unnecessary to close front feed lip 155 after each sheet is inserted.

By the provision of the above parts, the operator may print headings on a number of sheets without having to manipulate the carriage in any manner between the successive printing operations.

OPERATION

In using the present construction, the operator first opens the front feed mechanism to the position shown in Figure 2 and inserts the front fed sheet. He then passes the journal sheet 7, together with the necessary carbon paper, over paper table 57 and inserts it downwardly until it stops where the rear feed rolls contact the platen. The platen is then rotated to bring the journal sheet 7 around the platen, the front fed paper serving as a guide for the leading edge of the journal sheet. The operator then moves brackets 138 downwardly on paper guides 118 to disconnect them from rod 135, and pivots guides 118 forwardly to the dot and dash position shown in Figure 2. This permits free access to complete insertion of the journal sheet. He then presses finger piece 85 and rotates the platen un- 70 75

til the journal sheet is between pressure finger 81 and the platen. He then continues rotating the platen, at the same time directing the paper, with his other hand, under tear plate 82. From 5 this point the journal sheet will feed automatically. The tally roll 8 is then fed around the platen in a similar manner except that there is no pressure finger 81 cooperating with the tally roll. Paper guides 118 are then moved to their 10 full line position shown in Figure 2. The front fed paper may then be adjusted to its proper location for printing and the front feed mechanism closed by the operator pressing rearwardly on rod 147 or the associated parts.

15 At a predetermined time the front feed mechanism is automatically opened, in the manner described in application Serial No. 150,367. The front fed sheet may then be removed and another inserted. At predetermined intervals the 20 platen is automatically advanced to line space the paper. When it becomes desirable to adjust the alignment of the journal sheet or tally roll, one of the levers 78 may be operated to move pressure roll 66 away from the platen. After 25 the paper is adjusted the lever is returned to its original position.

When it is desired to print headings in the same location on a number of front fed sheets, the auxiliary chute 186 is placed in position on 30 the front feed mechanism and lever 198 is operated to open front feed lip 155. The paper stops 164 are then adjusted in the manner disclosed in application Serial No. 92,164, so that the sheets may be inserted the proper extent 35 without the attention of the operator to the proper alignment thereof. The sheets may then be inserted, the headings printed, and the sheets

removed without further manipulation of the carriage.

While the form of mechanism herein shown and described is admirably adapted to fulfill the objects primarily stated, it is to be understood 5 that it is not intended to confine the invention to the one form of embodiment herein disclosed, for it is susceptible of embodiment in various forms all coming within the scope of the claims which follow.

10

What is claimed is:

1. In a paper carriage, a platen mounted on a fixed pivot, a front feed chute pivoted to swing forwardly and rearwardly in the machine, a movable guiding means for directing the front fed 15 paper in close proximity to the plate as it passes under the same, the guiding means having an open position away from the platen and a closed position in close proximity to the platen, means for moving the guiding means to closed position 20 by movement of the chute rearwardly, to curve the paper around the forward part of the platen, and a manipulative means to move the guiding means to its open position while the chute lies in 25 its rear position.

23

2. In a paper carriage, a front feed mechanism having a chute and a movable guiding means for aiding the insertion of front fed paper, the chute and guiding means being movable from a paper inserting to a closed paper feeding position, and an auxiliary paper chute detachably mounted on the front feed mechanism, for aiding the insertion of front fed paper when the first mentioned chute is in its closed position 30 and the guiding means is in its paper inserting 35 position.

WALTER A. ANDERSON.

CERTIFICATE OF CORRECTION.

Patent No. 2,185,424.

January 2, 1940.

WALTER A. ANDERSON.

It is hereby certified that error appears in the printed specification of the above numbered patent requiring correction as follows: Page 5, second column, line 16, claim 1, for "plate" read platen; and that the said Letters Patent should be read with this correction therein that the same may conform to the record of the case in the Patent Office.

Signed and sealed this 30th day of January, A. D. 1940.

(Seal)

Henry Van Arsdale,
Acting Commissioner of Patents.
